UNITED STATES PATENT OFFICE.

EMIL HOFFMANN, OF CHICAGO, ILLINOIS.

ACETYLENE-GAS LAMP.

SPECIFICATION forming part of Letters Patent No. 657,489, dated September 4, 1900.

Application filed February 26, 1897. Serial No. 625,123. (No model.)

To all whom it may concern:

Be it known that I, EMIL HOFFMANN, a citizen of the United States, and a resident of Chicago, Cook county, Illinois, have invented certain new and useful Improvements in Lamps, of which the following is a full, clear, and exact description, reference being had to the accompanying drawings and to the characters of reference marked thereon.

10 My invention relates to lamps that generate and burn acetylene gas. This gas, generated by applying water to calcium carbid, is so extremely volatile and penetrating that heretofore it has been difficult to control and regulate it.

15 The objects of my invention are to control the generation of the gas by regulating the supply of water to the calcic carbid, to regulate the pressure of the gas, and to make it assist 20 in controlling the water-supply. This I accomplish by means of a valve in the bottom of the water-chamber, which is controlled by the pressure of the gas beneath it, and by a valve controlled by the pressure of the gas in the 25 chamber from which the burner leads, whereby the flow of gas from the generating-chamber is controlled, substantially as hereinafter fully described and as illustrated in the drawings, in which—

30 Figure 1 is a vertical central section through my invention. Fig. 2 is a side view of the same. Fig. 3 is a horizontal section taken on dotted line 3 3, Fig. 1.

The case of my invention is cylindrical or 35 other suitable shape and is divided into two sections A and B, one of which, B, forms a circumambient gas-chamber b for the calcic-carbid receptacle C and screws up into the superimposed section A. Section A contains 40 a water-chamber D in its lower part, into which water can be introduced through a suitably-covered inlet a, projecting from the side of the case, and contains a gas-chamber E, which is separated therefrom by suitable partitions, as will hereinafter more fully appear.

45 The bottom c of the water-receptacle consists of a plate which closes the lower end of section A and is provided near its outer edge with an annular downwardly-extending 50 flange b', the outer circumference of which is threaded, so as to receive the upper inte-

riorly-threaded thickened edges of the lower section B, which latter thus comes between the lower edges of section A and flange b', and by pressing up against a suitable rubber packing-ring a' makes a gas-chamber b perfectly air-tight. The center of bottom c is provided with a countersunk opening d therethrough, which is closed on its upward movement by a valve carried on the lower end of a valve-stem e, and said bottom is provided with concentric upwardly-projecting and downwardly-projecting annular flanges or walls c' and f, respectively, preferably of a corresponding diameter and considerably less than the 65 diameter of flange b.

The calcic-carbid chamber C is preferably cylindrical and of a less diameter and depth than section B, so as to provide the circumambient gas-chamber b, and its lower end is 70 closed by a removable bottom F, the center of which is provided with a suitable perforation F². The upper end of chamber C is provided with a neck m, consisting of a short tubular stub projecting up centrally therefrom, 75 which is of such diameter as to permit it to be inserted and tightly fitted in or onto the annular flanges f of the bottom c of the water-chamber.

The valve-stem e extends centrally upward, 80 and its upper end, above the collar e' thereof, enters the compression-drum G. This compression-drum G is suspended centrally in the water-chamber between the upper end of said valve-stem e, upon the collar e' of which 85 its lower head rests, and a stud g, depending centrally downward from the transverse partition h, forming the top of the water-chamber. The lower end of this stud g enters the upper head of drum G, and it has a collar g', 90 that bears against said upper head. Now the heads of drum G are made of thin elastic sheet-steel, and so when the pressure of gas in the water-chamber is sufficient the heads of the drum will be depressed or compressed 95 inward toward each other, so as to move valve-stem e upward and close the valve. When the pressure of gas in the water-chamber diminishes sufficiently, the heads of the drum, assisted by a coil expansion-spring G' 100 in said drum, will expand outwardly away from each other, and thus move the valve-

stem downward and open the valve-opening to permit the water to pass therethrough into the carbid-chamber.

The lower end of the valve-stem *e* is provided with an inverted conical-shaped valve-head *M'*, which comes within the neck *m* of the calcic-carbid chamber and the screw-threaded shank of which is tapped longitudinally and centrally into the lower end of valve-stem *e*. The inverted base of this conical valve-head is provided with a suitable leather washer and practically constitutes the valve for closing the opening communicating with the water-chamber and carbid-chamber. By screwing or unscrewing this head *M'* the reciprocal movement of the valve is regulated as desired.

Ordinarily the gas pressure is such that the valve-stem *e* moves up and down, according to the variations from the normal pressure, which is determined by the elasticity of the heads of the compressible drum and the stroke of the valve-stem and permits just water enough to enter the carbid-chamber from the water-chamber to maintain a given generation and pressure of gas all the time. The gas generated in the carbid-chamber in order to find egress therefrom has to force its way down through the body of calcic carbid, which dries the gas which issues from the perforations *F*² into the circumambient gas-chamber *b*, and thus the surcharging of the gas with moisture, as is usually the case, is avoided. From the chamber *b* the gas passes through a vertical pipe *i*, extending from the bottom *c* up through the water-chamber into an antechamber *I*, made by transverse partitions *x x* in the part of the section *A* of the case above the water-chamber. In the lowermost of these partitions *x* and in an intermediate partition *y* (which can be dispensed with, if desired) and in the partition constituting the top of the water-chamber *I* I provide small holes 1, 2, and 3, down through which the water accidentally forced up into chamber *I* or resulting from the condensation of heated gas therein can drain back into the water-chamber and down through which the gas finds egress to the water-chamber to operate the compressible drum and valve connected therewith. In the uppermost partition *x*, enclosing the antechamber *I*, preferably nearer one side, is a discharge-opening *n*, the flow of gas out through which into the storage or supply-chamber *E*, occupying the top portion of section *A*, is controlled by a valve *K*. Valve *K* is suitably secured to the end of a lever *J*, which is fulcrumed at about its center of length and the end of which opposite said valve *K* terminates about the center of the lamp. This end of lever *J* opposite the valve is connected by a vertical rod *o* to a drum *N*, which is suspended in position between the upper end of said rod *o* and the lower end of a hanger *p*, depending centrally in alignment therewith from the center of the top of the case. Drum *N* is constructed and operates

identically like drum *G*, except as to dimensions. Thus when the pressure of the outflowing gas in chamber *E* is at or below normal the natural expansion of the drum depresses the centrally-terminating end of lever *J* and raises the valve *K*, and when the pressure of the gas in said chamber *E* is above normal it causes the compression of the drum, 75 and this causes the valve to close. Leading down from the supply-chamber is a pipe *M*, which extends down into the water-chamber, where it is bent laterally and is connected to the nipple *r*, to which the burner *P* is attached. This pipe *M* may, however, be dispensed with and the burner be connected directly to and lead from chamber *E*. 80

The operation of my invention is as follows: The cock in the burner being turned and the 85 gas flowing therefrom ignited, the gas is primarily rarefied in chamber *E*. This causes valve *K* to open and relieves the chamber, and thus leaves drum *G* free to expand and move the valve-stem *e* downward and permits the water to flow through openings *k k* in the wall *c'*, surrounding the lower end of the valve, and through opening *d*, around the lower end of the stem of the valve, into the carbid-chamber to cause further generation of the gas, 95 whereupon the action of the several parts of the lamp continue to operate as hereinbefore explained.

I do not wish to be confined to the exact mechanical construction of my improved lamp 100 as shown or to the particular kind of valves described or their exact arrangements, for so long as their construction and arrangement of the different elements and features accomplish the same results, as hereinbefore described, I consider them as coming within the spirit of my invention.

What I claim as new is—

1. In an acetylene-lamp a calcic-carbid chamber and a valve-controlled superimposed water-chamber, of an antechamber having a perforate bottom through which communication can be had to the water-chamber to allow access of gas to said water-chamber, a supply-chamber provided with an opening whereby communication can be had with said antechamber, a valve-controlled burner leading from said supply-chamber, and a valve controlling the communicating opening between said antechamber and supply-chamber, as 115 and for the purpose set forth.

2. In an acetylene-lamp, the combination with a gas-generating chamber, and a superimposed water-chamber communicating therewith, of a supply-chamber arranged above said water-chamber and an antechamber interposed between said supply and water chambers having valved connections with said supply-chamber and having also connections with the water and generating chambers, 125 substantially as set forth.

3. In an acetylene-lamp, a gas-generating chamber, in combination with a superimposed water-chamber, which is open to the gas-

pressure therefrom, and which has an opening in its bottom communicating with said generating-chamber, a valve controlling said opening, a compressible drum suspended in 5 said water-chamber to which said valve is connected, said drum being exposed to the gas-pressure from all sides, a supply-chamber above said water-chamber connected by suitable passages with said generating-chamber, 10 and a valve controlling the ingress of gas from the generating-chamber into the supply-chamber.

4. In an acetylene-lamp, a gas-generating chamber, in combination with a superimposed 15 water-chamber to which said gas-generating chamber is removably secured, which is open to the gas-pressure therefrom and which has an opening in its bottom communicating with said generating-chamber, a valve controlling 20 said opening, a compressible drum suspended in said water-chamber to which said valve is connected, an antechamber immediately above said water-chamber connected by suitable passages with said generating-chamber, 25 a supply-chamber above said antechamber, and a valve controlling the ingress of gas from the antechamber into the supply-chamber.

5. In an acetylene-lamp, a calcic-carbid receptacle provided with a short tubular neck and with suitable perforations for the escape 30 of gas, and a lower section of the shell of the lamp within which said receptacle is placed in such manner as to leave a gas-circulating chamber between the two, in combination with a superimposed water-chamber to which said lower section is removably secured, which has an opening in its bottom provided with downwardly-projecting annular flanges to 35 40 which said calcic-carbid receptacle is connected by means of its said neck, and which is open to the gas-pressure from said lower section, a valve controlling said opening, a compressible drum suspended in said water-chamber, to which said valve is connected by suitable passages with said lower section, and a valve controlling the ingress of gas from the generating-chamber.

6. In an acetylene-lamp, a calcic-carbid receptacle provided with a short tubular neck and with suitable perforations for the escape 45

of gas, and a lower section of the shell of the lamp within which said receptacle is placed in such manner as to leave a gas-circulating chamber between the two, in combination with a superimposed water-chamber to which 55 said lower section is removably secured, which has an opening in its bottom provided with downwardly-projecting annular flanges to which said calcic-carbid receptacle is connected by means of its said neck, and which is open to the gas-pressure from said section, a valve controlling said opening, a compressible drum suspended in said water-chamber to which 60 said valve is connected, an antechamber connected by suitable passages with said circulating-chamber in the lower shell, a supply-chamber above said antechamber, and a valve controlling the ingress of gas from the antechamber into the supply-chamber. 70

7. In an acetylene-lamp, a calcic-carbid receptacle provided with a short tubular neck and with suitable perforations for the escape of gas, and a lower section of the shell of the lamp within which said receptacle is placed 75 in such manner as to leave a gas-circulating chamber between the two, in combination with a superimposed water-chamber to which said lower section is removably secured and which has an opening in its bottom provided 80 with downwardly-projecting annular flanges to which said calcic-carbid receptacle is connected by means of its said neck and which is open to the gas-pressure from said lower section, a valve controlling said opening and 85 a burner, as and for the purpose set forth.

8. In an acetylene-lamp, the combination with a gas-generating chamber and a superimposed water-chamber having an opening in its bottom communicating with the said generating-chamber, of a pressure-controlled device located in the water-chamber, a valve-stem connected thereto and extending into proximity to said opening, and a valve-head adapted to close said opening connected to 90 said stem and adjustable thereon, whereby the pressure required to operate said valve may be regulated.

EMIL HOFFMANN.
